CLAIM

We claim the ornamental design for a knife, as shown and described.

DESCRIPTION

FIG. 1 is a front perspective view of the knife showing our new design;

FIG. 2 is a front elevation thereof;

FIG. 3 is a back elevation thereof;

FIG. 4 is a left end elevation thereof;

FIG. 5 is a right end elevation thereof;

FIG. 6 is a top plan view thereof; and,

FIG. 7 is a bottom plan view thereof.
